ION SOURCE UNIT FOR A CALUTRON

William M. Brobeck, Oak Ridge, Tenn., assignor to the United States of America as represented by the United States Atomic Energy Commission

Application May 22, 1945, Serial No. 595,194

2 Claims. (Cl. 250—41.9)

The present invention relates to calutrons and, more specifically, to ion-producing mechanism for use in a calutron. In one aspect the present invention comprises an improvement upon ion-producing mechanism of the type disclosed in Letters Patent of the United States, No. 2,709,222, issued May 24, 1955, to Ernest O. Lawrence. Reference is made to that patent for a full account of the nature of a calutron and the theory of its operation.

As disclosed in the patent, a calutron comprises an evacuated vessel disposed in a powerful magnetic field and containing apparatus by means of which a substance containing a plurality of isotopes, or comprising a mixture of elements, is vaporized and then ionized. The ions are projected as a narrow beam through the evacuated vessel, and the influence of the magnetic flux causes the beam to follow a curved path. Ions of greater mass tend to concentrate in that portion of the beam adjoining the outer periphery of the curve, and ions of less mass tend to congregate in that portion of the beam adjacent the inner periphery of the curve. By placing a collector including a plurality of pockets, in the path of the beam it is possible to collect aggregates in which the distribution of isotopes has been altered from that of the initial, or charge, material. For example, uranium as it normally occurs is constituted by three of its isotopes, U^{234} , U^{235} , and U^{238} . When a uranium compound is treated in a calutron the product is a pair of aggregates of which one has been enriched with respect to U^{235} and U^{234} , while the other aggregate has been increasingly impoverished with respect to these lighter isotopes.

One of the problems encountered in the construction and operation of calutrons is the provision of an arc capable of ionizing a satisfactorily large percentage of the vaporized charge material. It has been found that when voltages high enough to generate a suitable arc are employed, usually by the combination of an electron-emissive filamentary cathode and an ionization chamber having walls maintained at positive potential, the copious emission of electrons in undesired directions from the filament causes rapid deterioration of adjacent elements of the mechanism.

Another disadvantage found in the operation of prior calutrons has been the short life of the filament, a characteristic due in part to the fact that the emission of electrons from the filament has taken place throughout its length, with the result that the electron-emissive material of the filament is rapidly exhausted and rendered excessively frangible.

The most important object of the present invention is to improve the performance of the ion-producing mechanism employed in a calutron.

Another object of the invention is to confine the emission of electrons from the filament toward the ionization chamber in order to prevent bombardment and erosion of adjacent members.

Another object of the invention is to increase the life of a calutron filament by limiting the emission of elec-

2

trons to a relatively small, predetermined segment thereof.

An important feature of the invention resides in the interposition of an apertured shield plate between the ionization chamber and the filament, the shield plate and the filament being so disposed that the aperture in the shield plate underlies only a relatively short segment thereof.

Another feature of the invention resides in the combination of the shield plate referred to in the foregoing paragraph and a second shield plate arranged to overlie the entire filament, both shield plates being electrically connected to the filament, with the result that electrons are emitted from the filament only from a short segment thereof and only in the direction of the aperture in the lower shield plate which overlies the ionization chamber.

These and other objects and features of the invention will be more readily understood and appreciated from the following detailed description of a preferred embodiment thereof selected for purposes of illustration and shown in the accompanying drawings, in which:

Figure 1 is a view partly in side elevation and partly in cross section showing a portion of a calutron constructed and arranged in accordance with the invention.

Fig. 2 is a view in exploded isometric showing ion-producing mechanism for a calutron constructed and arranged in accordance with the invention, and

Fig. 3 is a view in side elevation of the ion-producing mechanism.

No attempt is made herein to disclose a complete calutron. For this material, reference is made to the above-mentioned patent of Ernest O. Lawrence.

In Figure 1 there is shown, somewhat diagrammatically, the source end of a calutron, or that portion of the apparatus containing the ion-producing mechanism. Between the upper pole face 10 and the lower pole face 12 of a powerful magnet there is placed a tank or vessel 14 adapted to be evacuated (by means not shown) to a pressure of from 10^{-4} to 10^{-5} millimeters of mercury. The tank 14 has a side wall 16 having a large circular aperture 18 through which passes a tubular stem 20 insulated from the tank 14 and supported by means of a large heavy glass insulator 26. There is also provided mechanism designated generally by the reference character 28 by means of which the stem 20 may be universally adjusted with respect to the tank 14. The details of the adjusting mechanism are fully disclosed in the above-mentioned patent of Ernest O. Lawrence.

The stem 20 terminates at its inner end in a rod 22. Welded to the end of the rod 22 is a rectangular metal plate 32 in each corner of which is a hole receiving a screw 38 which passes through the plate 32, through a tubular spacer 36 and into a hole tapped into a metal block 34. The four screws 38 thus serve to mount the block 34 at the end of the rod 22. The block 34 is provided with a vertical bore in which is mounted an electric heating element including a core 40 of ceramic material upon which is wound a length of high resistance wire 42. A disk 44 overlies the heater chamber and supports a screw 46 which engages a hole tapped in the upper end of the core 40 and serves to mount the heater in its position in the block 34. The core 40 is enlarged at its lower end as shown at 48 and provided with a depending flange 49 which serves as a terminal block for a pair of leads 50 and 52 which are suitably connected to the ends of the wire 42. The negative lead 50 is grounded to the rod 22, while the positive lead 52 is connected to a rigid conductor 30 which is mounted 70 below and parallel to the stem 20.

At the far end of the block 34 there is a second vertical bore 54 which serves as a vaporizing chamber and

charge receptacle. Before the calutron is operated, a quantity 56 of material such as UCl_4 is dropped into the bore 54. A slot 58 is milled in the block 34 and intersects the bore 54, thus providing a restricted exit passage from the charge chamber 54. A flat rectangular plate 60 is secured to the top of the block 34 by means of four screws 62 and is provided with an aperture 64 of small diameter which is disposed to overlie the center of the slot 58.

Mounted above and parallel to the stem 20 is a pair of stiff tubular conductors 24 surrounded by a pair of water jacket tubes 66. The jackets 66 extend beyond the end of the conductors 24 and terminate above the block 34. To one of the water jackets 66 there is secured an L-shaped metal block 68 which cooperates with a rectangular block 70. The blocks 68 and 70 are provided with matched grooves, in which the end of a substantially U-shaped filament 72 is received, and the block 70 is drawn into clamping engagement with the block 68 by means of a pair of screws 71. The other of the water jackets 66 terminates in a metal block 74 which has an integral plate 76 extending therefrom and overlying the filament 72. The block 74 is cut away to form a recess on its lower side, the recess being filled by a second block 78 having an integral plate 80 extending therefrom in position to underlie the filament 72. The block 78 and the plate 80 are drawn into engagement with the block 74 by means of a pair of screws 82, and the other end of the filament 72 is clamped between the blocks 74 and 78, there being grooves (not shown) in which the end of the filament is received.

Extending through the plate 80 is a circular aperture 84 which is axially aligned with the aperture 64 in the plate 60 and which underlies a centrally disposed segment of the filament 72.

When the device is to be operated the circuits are closed to impress about four volts across the filament 72 and to render the arc block 34 approximately 200 volts more positive than the filament 72. The plates 76 and 80 are connected to the most negative side of the filament 72. The material of which the filament 72 is made is not critical, since any electron-emissive substance commonly used as a filament can be employed herein; tungsten and tantalum are examples of filament materials which have successfully been employed in calutrons.

Inasmuch as the plate 76 is at the same potential as the filament or slightly negative with respect thereto, the emission of electrons from the filament in the direction of the plate 76 is substantially eliminated. Consequently, all parts of the calutron lying above the filament are protected against deterioration due to the bombardment by electrons leaving the filament. Similarly the plate 80 serves to limit the emission of electrons from the filament 72 to that portion thereof which lies directly over the aperture 84. It should be further understood that the action of the powerful magnetic field in which the mechanism is placed serves to confine the emission of electrons to planes parallel to the direction of the magnetic flux. The diameter of the aperture 84 must be sufficiently great to avoid a grid effect from the plate 80. In other words, the fact that the plate 80 is connected to the most negative leg of the filament would tend to render it a grid functioning to limit the emission of the electrons from any portion of the filament. However, if the aperture 84 is made large enough the grid effect is obviated or reduced to negligible portions. The plate 60 is, of course, at the same potential as the arc block 34, or 200 volts more positive than the filament 72. Consequently, electrons emitted from the filament 72 are strongly attracted toward the arc block 34 and the stream of electrons

which form the arc travels from the filament through the apertures 84 and 64 and down through the slot 58 in the arc block 34.

When the heating element is energized the walls of the chamber 54 are elevated in temperature until the charge material 56 is caused to vaporize. Due to the vacuum in the vessel 14 the vapor thus formed is drawn through the slot 58 where it encounters the arc discharge. The electrons in the arc impinge upon the vapor molecules to cause dissociation and ionization thereof, and further ionization is caused by secondary collision.

By placing accelerating electrodes (not shown) in advance of the slot 58 and applying to them a potential highly negative with respect to the arc block 34, positive ions are withdrawn from the slot 58 or ionization chamber and accelerated to form a dense high-velocity beam of positive ions.

It should be noted that, although the arc passes through the aperture 64 in the cover plate 60, that portion of the plate 60 which immediately surrounds the aperture 64 will be subjected to some erosion due to electron bombardment. However, it is an easy matter to replace the plate 60 as it wears away, and it is to be noted that the arc block 34 is substantially protected from electron bombardment by the shield plate 80. As previously disclosed, the upper shield plate 76 serves to prevent the electron bombardment of all the elements of the calutron which overlie the filament 72. Furthermore, the lower shield plate 80 and the aperture 84 function to prevent the emission of electrons from the filament 72 except from that portion or segment of it which directly overlies the aperture 84 and is therefore subject to the influence of the voltage drop between the filament and the arc block 34. By thus confining the emission of electrons from the filament to a relatively short segment thereof, the life of the filament is substantially increased and the effectiveness of the ion-producing mechanism greatly improved.

Having now described and illustrated the embodiment 40 of my invention, what I claim as new and desire to secure by Letters Patent of the United States is:

1. Ion-producing mechanism which comprises a substantially U-shaped filament, an imperforate shield plate disposed to overlie said filament and electrically connected thereto, an apertured lower shield plate electrically connected to said filament and disposed to underlie said filament except for a linear portion thereof, and a source block having an ionization chamber disposed beneath said filament and having a passage aligned with the aperture in said lower shield plate to afford communication from said chamber to said filament.

2. An ion source mechanism which comprises a source block having an ionization chamber, a cover plate covering one end of said chamber except for an aperture extending through said plate, a substantially U-shaped filament suspended with a linear portion thereof above the aperture in said cover plate, and a pair of shields electrically connected to said filament and disposed respectively above and below said filament, the lower shield having an aperture aligned with the aperture in said cover plate.
